RAZOR BLADE SCRAPER

Alan C. Ferguson, Southbridge, Mass., assignor
to Hyde Manufacturing Company, South-
bridge, Mass., a corporation of Massachusetts

Application February 13, 1953, Serial No. 23,609

Term of patent 14 years

(Cl. D8—6)

To all whom it may concern:

Be it known that I, Alan C. Ferguson, a citizen of the United States, residing at Southbridge, in the county of Worcester and State of Massachusetts, have invented a new, original, and ornamental Design for a Razor Blade Scraper, of which the following is a specification, reference being had to the accompanying drawing, forming part thereof.

Fig. 1 is a plan view of a razor blade scraper with the blade retracted, showing my new design;

Fig. 2 is a plan view showing the opposite side thereof;

Fig. 3 is an edge view thereof;

Fig. 4 is a front view, looking in the direction of arrow 4 in Fig. 2; and

Fig. 5 is a cross-sectional view taken on line 5—5 of Fig. 1.

The dominant features of my design reside in those portions shown in full lines.

I claim:

The ornamental design for a razor blade scraper, as shown and described.

ALAN C. FERGUSON.
